UNITED STATES PATENT OFFICE.

GEORGE W. TODD, OF OMAHA, NEBRASKA.

DENTAL BRIDGEWORK.

1,118,703.

Specification of Letters Patent. Patented Nov. 24, 1914.

Application filed March 25, 1914. Serial No. 827,117.

To all whom it may concern:

Be it known that I, GEORGE W. TODD, a citizen of the United States, residing at Omaha, in the county of Douglas and State of Nebraska, have invented certain new and useful Improvements in Dental Bridgework, of which the following is a specification.

This invention relates to improvements in dental bridge work, and has for its object to provide such a construction that porcelain bases may be maintained side by side to have the appearance of natural teeth, the binding or supporting medium consisting of connected metallic caps. The invention includes the provision of suitable facets formed on the tops of the bases and corresponding facets formed on the bottoms of the caps, so that these contacting parts may have suitable engagements or bearings, and means for securing each base to a cap.

The invention consists of the novel construction, combination and arrangement of parts as described herein and claimed, and as illustrated in the drawing, wherein,—

Figure 1 is a plan view of a bridge. Fig. 2 is a front elevation of the same. Figs. 3 and 4 are views, respectively, of a cap and a base, to clearly show the construction of these parts, the views being on an enlarged scale and in longitudinal section on line 3 4 of Fig. 1. Figs. 5 and 6 are views in longitudinal section respectively of the cap and base, the view being on line 5 6 of Fig. 1, on an enlarged scale. Fig. 7 is a view in longitudinal section of a plurality of connected caps to form the metallic part of a bridge, this being a modified form of the invention. Fig. 8 is a view in longitudinal section of one of the caps shown in Fig. 7, said section being taken through one of the T-shaped slots or recesses. Fig. 9 shows three bases in longitudinal section provided with facets and lugs for engaging the respective facets and grooves of the caps shown in Fig. 7. Fig. 10 is a view in longitudinal section of one of the bases shown in Fig. 9, the section being at right angles to the section shown in said Fig. 9.

Referring now to the drawing for a more particular description, the bridge shown in Figs. 1 and 2 consists of a plurality of teeth 1 disposed between two terminal crowns 2, each of the teeth 1 consisting of a base 3 and a cap 4.

The bases are preferably constructed of porcelain, their bottoms being of saddle

shape so that they may bear firmly on the gums. As shown in the drawing, their tops are provided with facets *a* and facets or recesses *b*, facet *a* being of convexed form and disposed at right angles to the longitudinal axis of the base, and facets or recesses *b* each providing a wall which is inclined outwardly and downwardly with reference to facet *a* and extending substantially from the front to the rear sides of each base; and as shown in Figs. 4 and 6 prongs or pins *c* are disposed above the facets *a* while mounted in the bases.

The caps are preferably constructed of metal and as shown in Figs. 3 and 5 they are provided with the facet *d* of convex form and outwardly of said facet, are provided with projections or flanges *e*, and when a base is placed in contact with the cap to which it belongs, the surface of its facet *a* will engage the surface of the facet *d* of the cap, the flanges of the cap being adapted to fill the recess *b* of the base, the prongs or pins of the base engaging in apertures or recesses *h* of the caps.

Since the facet of each base is formed angular with reference to its recesses, the relation of the facet of each cap being also angular with reference to its flanges, they are adapted to sustain the stresses incident to their use, when assembled, and this construction is preferred for the further reason that these projections provide an additional area for connecting with solder when the metallic caps are connected side by side. It is obvious however that other recesses could be employed than those shown, and the result would be practically the same, and I do not wish to be understood as limiting myself to the number of facets, recesses or flanges to be employed, nor to any particular curvature or conformation of surfaces for the inner contacting ends of the bases and caps.

In the practice of the invention, it will be understood that the metallic caps and crowns 2 may be disposed side by side and secured together by solder *w* or the metallic parts may be cast or molded as an integral structure, and the bases 3 are then separately secured to the caps by any suitable means, as by use of solder or cement, to form a complete bridge.

In the modified form of the invention, Fig. 7 shows a plurality of metallic caps 4' and crowns 2' disposed side by side and

secured together by solder α' , or these metallic parts may be cast or molded as an integral structure. They are each provided at their sides with flanges e' and an intermediate facet d' and with slots or recesses 5 of T-shape opening on their facet d' and posterior side. At $3'$ are indicated porcelain bases each having a bottom of saddle shape and having a top provided with a 10 facet a' , and having facets or recesses b' at its sides which open on its facet a' , and having prongs c' substantially of T shape.

Each base $3'$ may have a slidable movement with reference to the particular cap 15 $4'$ to which it belongs, of the metallic part of the bridge, to dispose its prongs in the elongated T-shaped slots and after the bases are thus mounted they may be secured thereon by soldering, cementing or other suitable 20 means. While the holding means provided by the modification is somewhat different than the means first described, it is not considered to be a departure, for the reason that the invention discloses a bridge consisting of two-part teeth provided at their inner contacting ends with interlocking devices and the particular form for these interlocking parts is largely a matter of choice.

Among some of the advantages to be derived by use of the invention, it may be stated that bridges constructed as described may present the appearance of natural teeth, the metallic part being at the posterior side of the bridge, also the work of constructing bridges is greatly simplified and may be more quickly performed; the porcelain bases provide a firm foundation for the bridge, and the metallic part thereof does not come in contact with the gums.

It will be noted that since porcelain is the only material making engagement with the gums, the metallic pockets ordinarily formed adjacent to the gums, and in which fermentation occurs from deposits of food, are by 45 this construction, wholly avoided.

Having fully described my invention, what I claim and desire to secure by Letters Patent is,—

1. A dental bridge comprising, in combi-

nation with a plurality of connected metallic 50 caps disposed side by side, said caps being formed with facets on their inner ends and having recesses opening on said facets, a plurality of base-members each having an end provided with a surface conforming 55 substantially to the shape of the facets of the caps for a mounting on one of said caps and provided with prongs adapted to engage in the recesses of said caps.

2. A dental bridge comprising, in combination with a plurality of connected metallic caps disposed side by side, said caps being formed with flanges on their inner ends extending between their anterior and posterior sides and having recesses opening 65 on said ends, a plurality of base-members each having an end provided with recesses conforming substantially to the shape of the flanges of the caps for a mounting on one of said caps, and provided with prongs adapted 70 to engage in the recesses of said caps.

3. A dental bridge comprising, in combination with a plurality of connected metallic caps disposed side by side, said caps being formed convexed on their inner ends and 75 having recesses opening on said convexed ends, a plurality of base-members each having an end provided with a concaved surface for a mounting on one of said caps and provided with prongs adapted to engage in 80 the recesses of said caps.

4. A dental bridge comprising, in combination with a plurality of connected metallic caps disposed side by side, each being provided with holding-devices, a plurality of 85 base-members each being provided with holding-devices and adapted to have a mounting of one of its ends on the end of one of said caps, said holding-devices on said base-members and caps moving into 90 engagement for connecting each base-member with one of said metallic caps.

In testimony whereof, I have affixed my signature in presence of two witnesses.

GEORGE W. TODD.
